United States Patent Office

Des. 191,870
Patented Dec. 5, 1961

191,870

AWNNG ORNAMENT OR SIMILAR ARTICLE

Vaughn Pedersen, Mount Prospect, Ill., assignor to Ken-ron Awning & Window Corporation, Chicago, Ill., a corporation of Illinois

Filed Nov. 14, 1960, Ser. No. 62,833

Term of patent 14 years

(Cl. D21—1)

FIG. 1

FIG. 2

FIG. 4

FIG. 1 is a side elevational view of an awning ornament embodying my new design;

FIG. 2 is a top plan view thereof;

FIG. 3 is an end view thereof as seen from the left of FIG. 1; and

FIG. 4 is another end view thereof as seen from the right of FIG. 1.

I claim:

The ornamental design for an awning ornament or similar article, as shown.
